C. W. ATKESON.

Sugar Evaporator.

No. 17,548.

Patented June 16, 1857.

UNITED STATES PATENT OFFICE.

CHARLES W. ATKESON, OF HENDERSON, KENTUCKY.

IMPROVEMENT IN BRINE-EVAPORATORS.

Specification forming part of Letters Patent No. 17,548, dated June 16, 1857.

To all whom it may concern:

Be it known that I, CHARLES W. ATKESON, of Henderson, in the county of Henderson and State of Kentucky, have invented a new and Improved Evaporating and Steam Generating Apparatus or Boiler, by the use of which I am enabled to speedily and economically reduce salt-water to the state at which it must be run off into granulating-vats, and also at the same time produce a sufficient quantity of steam in said apparatus to be conducted therefrom into heating-pipes in the aforesaid vats to complete the granulating process therein as fast as the strong brine is conducted into them from the said evaporating apparatus; and I do hereby declare that the following is a full and exact description thereof.

In the accompanying drawings, Figure 1 is a vertical section cut through the center of the aforesaid apparatus, and Fig. 2 is a section in the line *y y* of Fig. 1.

Similar letters indicate the same parts in both figures.

A is a furnace, constructed in any suitable and proper manner. B is a water-tight chimney rising from said furnace and passing through the central portion of an inclosing-boiler, C, which has a closed enlargement, D, at its upper extremity. Series of transverse tubes *aa*, arranged in tiers one above the other, pass through the said chimney B and open freely into the boiler C, while the connecting-joints between said tubes and the sides of the chimney are made water-tight. It will therefore be perceived that the said series of tubes *aa* add very considerably to the capacity of the boiler C, at the same time that they add greatly to the efficient heating-surface acted upon by the products of combustion as they ascend from the furnace. The cover of the enlargement D at the head of the boiler C should be closed steam-tight around the chimney B. The salt-water may be admitted into the boiler C either at top or bottom through a close-jointed pipe. The enlargement D at the top of the boiler facilitates the evaporating process by furnishing an enlarged surface, from which the steam may freely rise and pass off into the heating-tubes in the granulating-vats. The said enlargement also serves to prevent a violent ebullition and foaming of the salt-water within the boiler. The salt-water should rise a short distance into the enlargement D at the top of the boiler. The

enlargement D of the boiler should be connected by suitable pipes with series of heating-pipes in a suitable number of broad and shallow granulating-vats of the usual proportions. The bottom of the boiler should be connected by a stop-cock closed eduction-pipe with the said granulating-vats. After the brine within the boiler has been sufficiently concentrated, it should be conducted into the granulating-vats, which are heated by the steam generated within said boiler, and its place be supplied with salt-water as rapidly as the said concentrated brine is allowed to run off into the said granulating-vats. The concentrated brine should be allowed to pass off into the granulating-vats as rapidly as the process of granulation takes place within said vats.

It will be perceived that the series of horizontal tubes *aa* in my evaporating apparatus, while they add vastly to the heating-surface and produce a free circulation of the brine throughout the boiler, do not produce violent agitation therein, nor are the currents sufficiently rapid to cause a foaming action within the boiler, which assuredly would be the case provided the said tubes were arranged in vertical positions.

In my apparatus I effect exactly what is desired in the process of concentrating salt-water—viz., a very rapid evaporation without injurious agitation of the brine within the boiler, and all with the greatest economy of space, fuel, and labor.

I am aware that a series of horizontal tubes have been combined with the flue of a vertical cylindrical steam-boiler, and therefore I do not claim said arrangement as my invention; but

What I do claim, and desire to secure by Letters Patent, is—

Combining a series of horizontal heating-tubes with a vertical flue or chimney, when said flue or chimney is combined with an inclosing vertical casing which has an enlargement at its upper end entirely above the uppermost of the said heating-tubes, substantially as herein set forth.

The above specification of my new and improved evaporating apparatus signed and witnessed this 24th day of February, 1857.

C. W. ATKESON.
